UNITED STATES PATENT OFFICE.

VILAS H. JACKSON, OF CLEVELAND, OHIO.

EXCAVATING-BUCKET.

1,401,782.

Specification of Letters Patent. Patented Dec. 27, 1921.

Application filed June 28, 1920. Serial No. 392,236.

To all whom it may concern:

Be it known that I, VILAS H. JACKSON, a citizen of the United States, residing at Cleveland, in the county of Cuyahoga and State of Ohio, have invented certain new and useful Improvements in Excavating-Buckets, of which the following is a specification, reference being had to the accompanying drawings.

10 This invention relates to excavating buckets and more particularly to a bucket adapted for use in all kinds of excavating operations and with most types of excavating machinery which are at present in use.

15 An important object of the invention is to provide a bucket of this type wherein the operation of the bucket is semi-automatic.

20 A further object of the invention is to provide a bucket of the type described which may be readily adjusted for use in various kinds of work and soils, and in which such adjustments may be made with a minimum expenditure of labor and time.

25 A further object of the invention is to provide a bucket which in its various sizes is particularly adapted to strip coal and ore lands, quarries, level town sites, make cuts and fills in railway and highway construction, and in fact upon all manner of construction operations such as dam and mill ponds, bridge approaches, levees, ditches, subways and cellars, and for unloading open top scows and storage bins.

30 A further object of the invention is to provide a bucket which requires but an instant's light and safe work at the site of excavation immediately before and after filling, from but one laborer who may also act as a signal man, and with which the dragging of the 35 load to dump, dumping, righting and returning the bucket to excavation are entirely controlled by the engineer from his proper place, by manipulation of the controlling cables.

40 Further objects and advantages of my apparatus will become apparent throughout the course of the following description.

45 In the accompanying drawings, wherein for the purpose of illustration is shown a preferred embodiment of my invention and 50 wherein like reference characters designate like parts throughout:

Figure 1 is a plan view of my bucket.

Fig. 2 is a detail view of one of the outer digger teeth employed in my bucket.

55 Fig. 3 is a detail view of the same digger

tooth taken at right angles to the view shown in Fig. 2.

Fig. 4 is a side elevation of my bucket.

Fig. 5 is a detail sectional view illustrating the arrangement of the chain guide and chain pawl.

Fig. 6 is a plan view of the chain guide employed.

Fig. 7 is a detail view showing the manner of attaching the bail chains to the main haul line, and

Fig. 8 is a fragmentary detail view showing the notches formed in the rear wall of the shell.

Referring now more particularly to the drawings, the numeral 10 indicates the usual bucket shell which, in the construction of the device, will be made in various sizes in accordance with the requirements of the work. This shell is provided with the usual open 70 front end and top and is provided upon the bottom and rear surfaces thereof with reinforcing strips or shoes 11 which contact the ground and prevent undue wear upon the shell 10.

The bucket is provided upon the forward edge of the bottom thereof with excavating teeth 12 and 13, secured thereto in any suitable manner. The teeth 12, or end teeth, are of the usual construction and require no further description. The teeth 13, or outer teeth are situated adjacent the sides of the bucket at the bottom edge thereof and are provided upon their outer surfaces with outstanding integral lugs 13' which pivotally 90 receive the side arms 14 of a bail. The bail arms 14 are held in position by means of braces 40 having engagement with the pivots 13' as at 41 and secured rearwardly to the shell 10.

These side arms 14 are provided at their lower ends or those ends thereof adjacent the pivot 13' with a forwardly disposed cutting point 15 which normally engages the ground as the bucket is slid thereover and with a rearwardly extending foot 16 provided with a sharpened anchor point or tooth 17 for use in dumping on slippery grades. The arms 14 extend vertically a short distance and are then provided with a bend and extend forwardly from the bucket. By inspecting the drawings it will be seen that while these forwardly extending portions are approximately horizontal the tooth 17 is free from engagement with the ground and that when 100

105 110

the forwardly extending portions are shifted to, or slightly beyond, the vertical position, the tooth 17 comes into engagement with the ground.

5 The forward ends of the side arms 14 of the bail are spaced by a combined spacing and retaining member 18 which embodies a spacing sleeve 19 arranged intermediate the arms, and a bolt or retaining member 20 10 which extends through the arms and through the sleeve 19 and is held in position by nuts 21, the correct positioning of the sleeve 19 with the retaining member 20 being insured by sleeves 18' arranged in the ends 15 of the sleeve 19 through which the retaining member 20 extends.

The upper forward ends of the side wall of the shell 10 are spaced and positioned by a similar device embodying a sleeve 22 extending intermediate the inner walls of the shell 10 and provided in its ends with reducing sleeves 22'. A retaining member 23 extends through the sleeve 22 and through the side walls of the shell 10 and is 25 secured to said side walls in any suitable manner, preferably by riveting the ends of the retaining member 23 in order that these ends may be flush with the outer surface of the shell 10 to provide clearance for the 30 pivotally mounted side arms 14 of the bail.

Formed in the rear wall of the shell 10, centrally thereof and adjacent the top, is an opening 10'. Secured to the wall of the shell surrounding the opening 10' is a chain 35 guide 25 provided with the usual tapered right angular slots for the reception and guiding of the chain. Secured to the shell of the bucket, at or adjacent the heel 26 thereof, is an eye bolt 26' having secured thereto a chain 27 which passes through the opening 10' and chain guide 25 and has its forward end secured to a ring 43 rotatably mounted upon the bail arms spacing member 18. A short chain 44 has its rear 40 end connected to the plate 43 and its forward end pivotally connected with an open standard wire rope socket 28.

To the forward ends of the bail arms 14 are secured guys 29 having their forward 50 ends secured to the socket 28. The chain 44 is secured to the cross arm 18 of the bail at such a point that it becomes taut at the same time as the guy chains 29. The socket 28 has secured to its forward end a draft line or cable 31, hereinafter referred to as the main haul line.

The chain 27 is provided adjacent the rear end thereof with a link 45 embodying an upstanding shoulder or lug and adjacent the forward end thereof with a similar link 45. Intermediate the forward end of the chain 27 and the forward link 45 is arranged a stop link 46 embodying outstanding shoulders 47 adapted to engage the sides of the 65 guide 25 to limit rearward movement of

the chain. This stop link is preferably so arranged with relation to the forward link 45 that it engages the guide 25 as soon as the forward link 45 has passed sufficiently far therethrough to allow its engagement by 70 the pawl 33.

Arranged rearwardly of the opening 10' is a member 32 provided centrally with an opening aligning with the opening 10' and below such opening with the shoulder 32' 75 about which the chain 27 slides. To this member above the opening is pivotally connected a lever pawl 33 having a shoulder 34 adapted to engage the lugs of the links 45 of the chain to lock the same against being drawn through the opening 10' and guide 25.

It will be seen that when the chain is drawn sufficiently far rearwardly to allow the pawl 33 to engage the forward link 85 45 that the arms 14 are drawn well to the rear and the points 17 thereof will be in engagement with the ground. The type of chain used, which is the block chain having a straight upper surface will permit releasing of the pawl immediately after the stop link 45 with which it is engaged has passed, the shoulder of the pawl sliding upon the upper surface of the chain until it comes into engagement with the next stop link. It 90 will therefore be seen that if the pawl is in engagement with the forward link 45 it is elevated sufficiently to permit the forward pawl 45 to pass therethrough a pull upon the main haul line 31 will cause the arms 100 105 to move forward drawing the chain beneath the pawl 33 until the rear stop shoulder 45 is in engagement with the pawl when the movement is stopped. In this position the bucket is ready for the digging operation. 110 It will be obvious that when in this position if a pull is exerted upon the cable 38 the chain 27 will slide thereunder until the arms are drawn completely to the rear, bringing the brace member 18 of the cross arms 17 into 115 engagement with the notches 48 formed in the upper surface of the side walls of the shoulder 10 for the reception thereof.

A sheave 35 is provided embodying a chain wheel 36 which receives the chain 27 115 intermediate the eye bolt 26' and point which the chain passes through the opening of the member 32. Secured to the sheave 35 as by means of a taper socket joint 37, is a draft line or cable 38, hereinafter referred to as the out haul line.

When my bucket is being used for surface grading and is being operated by means of two drums winding up lines arranged at opposite ends of the grading operation, the 125 out haul line 38 is secured to one of said drums and the main haul line is secured to the other thereof. In beginning the operation the main line is slackened off and the out haul line tightened to move the bucket 130

to the point at which the excavating operation is to commence. The out haul line is now released and the field operator momentarily raises the lever pawl 33 disengaging the shoulder 34 thereof from the forward stop link 45 of the chain 27. The main haul line is now tightened and the chain moves through until it brings the rear stop link 45 thereof into engagement with the pawl shoulder 34, placing the bail arms 14 in the proper digging angle. The main line drum continues drawing on the main haul line 31 and the teeth 12 and 13 engage the earth, the teeth causing the rear end of the bucket 15 to elevate to the proper digging angle. When the bucket is filled the field operator raises the pawl allowing the bail arms 14 to drop and the bucket now slides freely upon the shoes 11 thereof to the dumping point. The main line drum is then slackened and the out haul line tightened drawing the bail arms 14 upwardly, automatically locking them in vertical position as the adjustable stop 46 reaches the guide 25 and throwing the teeth 17 into engagement with the ground, preventing sliding of the bucket when dumping down hill. The out haul line is then released and the main line engaged, the hooks 17 being in engagement with the ground and the forward extensions of the bail arms 14 being locked in approximately vertical position as indicated by the dotted lines in the drawing, the tension placed on the bail arms by the main haul line causes the bucket to dump, and the contents thereof to fall out. The main line is then released and the out haul tightened, pulling the bucket to an upright position. As this tightening is continued the bucket tilts so that it 40 rides upon the rounded heel 26 in its return to the starting point. In order to prevent cutting of the chains 29 when dumping I provide in the rear wall of the shell 10 notches 49 for the reception thereof.

It will be obvious that by the construction recited the amount of labor ordinarily required for dumping the bucket and returning same to normal position is eliminated and that the labor required of the field operator is not such that it requires great strength.

Owing to the principal construction of my bucket whereby in using and during filling the bucket requires no excess weight beyond that necessary to secure sufficient strength in construction it will accordingly be capable of manufacture at a relatively low cost.

Due to the bail fulcrum or pulling point of the bucket being located at the lower forward end thereof and comparatively close to the forward ends of the front of the teeth, it is practically impossible for my bucket to be primarily dumped from striking some

obstacle, as for example, some rock or stump 65 while filling or dragging the load to dump.

It will furthermore be obvious that by slight changes my bucket may be adapted for use in connection with radial boom type of excavator and may be used for many operations other than the one above described, which is presented merely for the purpose of showing one application of my device in practical usage.

In practice, this bucket for general excavation purposes and in transferring and dumping suitable materials for distances below one thousand feet, is found to accomplish the work in a most satisfactory manner and at a higher rate of speed than any known existing bucket. Due to the light weight of the bucket the depreciation of equipment and cost of operating are relatively low.

Cars, trucks and wagons may be loaded 85 for the use of my bucket by simply providing the usual inclined chutes having a stop for the bucket and a large opening at the point of dumping.

It will be still further obvious that many 90 obvious changes in the shape, size and arrangement of the various parts hereinbefore shown and described may be resorted to, and I accordingly do not limit myself to the specified structure hereinbefore set forth, but may make any such changes without departing from the spirit of the invention or the scope of the subjoined claims.

Having now described my invention, what I claim is:

1. In an excavating bucket, a shell, a bail embodying side arms pivotally connected with said shell at its forward end adjacent the bottom thereof, said bail being adapted to be adjustably positioned about the pivots thereof, a chain guide secured to the rear end of said shell approximately centrally thereof, a chain secured at one end to the exterior of the rear end of said shell, a cross arm connecting the side arms of said bail, said chain extending through said guide and being secured to said cross arm, and a tooth carried by each of said side arms, said teeth being out of engagement with the ground when the side arms are horizontally disposed and engaging the ground as the arms are shifted to the vertical position.

2. In an excavating bucket, a shell, a bail embodying side arms pivotally connected with said shell at its forward end adjacent the bottom thereof, said bail being adapted to be adjustably positioned about the pivots thereof, a chain guide secured to the rear end of said shell approximately centrally thereof, a chain secured at one end to the exterior of the rear end of said shell, a cross arm connecting the side arms of said bail, said chain extending through said guide and

- being secured to said cross arm, a tooth carried by each of said side arms, said teeth being out of engagement with the ground when the side arms are horizontally disposed and engaging the ground as the arms are shifted to the vertical position, a draft line secured to the free ends of said bail arms and adapted to shift said shell in one direction, a rotatable member engaging said chain intermediate its point of connection with said shell and said guide and a second draft line connected with said rotatable member and adapted to shift said shell in the opposite direction.
15. 3. In an excavating bucket, a shell provided rearwardly with a heel, a bail arm pivotally connected to each side of said shell at the forward end thereof adjacent the bottom, a chain secured to the outer surface of said shell adjacent the heel thereof, and operatively connected with said bail arms, a draft line connected to the free ends of said bail arms and adapted to move the shell in one direction, a draft line engaging said chain and adapted to move the bucket in the opposite direction, whereby said draft lines shift said bail arms about the pivots thereof, and means for engaging said chain to secure said bail arms against movement by said chain.
4. In an excavating bucket, a shell, a bail embodying side arms pivotally connected with said shell at its forward end adjacent the bottom thereof, said bail being adapted to be adjustably positioned about the pivots thereof, a chain guide secured to the rear end of said shell approximately centrally thereof, a chain secured at one end to the exterior of the rear end of said shell, a cross arm connecting the side arms of said bail, said chain extending through said guide and being secured to said cross arm, a tooth carried by each of said side arms, said teeth being out of engagement with the ground when the side arms are horizontally disposed and engaging the ground as the arms are shifted to the vertical position, means for locking the chain to prevent movement thereof and a stop adjustably mounted upon said chain intermediate said bail arms and said guide.
5. In an excavating bucket, a shell provided rearwardly with a heel, a bail arm pivotally connected to each side of said shell at the forward end thereof, a chain secured to the outer surface of said shell adjacent the heel thereof and operatively connected with said bail arms, the free ends of said bail arms being adapted for attachment to a draft line to move the shell in one direction, and a chain wheel engaging said chain and adapted for attachment to a draft line to move the shell in the opposite direction.
50. 5. In an excavating bucket, a shell, a bail embodying side arms pivotally connected with said shell at its forward end adjacent the bottom thereof, a chain guide secured to the rear end of said shell approximately centrally thereof, a chain secured at one end to the exterior of the rear end of said shell, a cross arm connecting the side arms of said bail, said chain extending through said guide and being secured to said cross arm, a tooth carried by each of said side arms, said teeth being out of engagement with the ground when the side arms are horizontally disposed and engaging the ground as the arms are shifted to the vertical position, and means for locking said chain to prevent movement thereof.
50. 5. In an excavating bucket, a shell, a bail embodying side arms pivotally connected with said shell at its forward end adjacent the bottom thereof, a chain guide secured to the rear end of said shell approximately centrally thereof, a chain secured at one end to the exterior of the rear end of said shell, a cross arm connecting the side arms of said bail, said chain extending through said guide and being secured to said cross arm, a tooth carried by each of said side arms, said teeth being out of engagement with the ground when the side arms are horizontally disposed and engaging the ground as the arms are shifted to the vertical position, and means for locking said chain to prevent movement thereof.

In testimony whereof I hereupon affix my signature.

VILAS H. JACKSON.
